UNITED STATES PATENT OFFICE.

JACOB EINSTEIN AND SEBASTIAN KORNPROBST, OF MUNICH, GERMANY

ELECTRIC METER.

SPECIFICATION forming part of Letters Patent No. 437,754, dated October 7, 1890.

Application filed January 14, 1890. Serial No. 336,873. (No model.)

To all whom it may concern:

Be it known that we, JACOB EINSTEIN, a subject of the King of Würtemberg, and SEBASTIAN KORNPROBST, a subject of the King 5 of Bavaria, residing both at Munich, Bavaria, Germany, have invented new and useful Improvements in Electric Meters and Indicators, of which the following is a specification.

This invention relates to improvements in 10 electric meters and recorders, which, when interposed at any point of the circuit, will at any moment indicate the current flowing through the circuit, (ampères, volts, watts,) and by means of a counting device the current 15 used during a certain space of time will be registered.

The essential feature of the invention consists in a revolving body communicating by 20 means of an intermediate connection with a registering device, the revolving body or the intermediate connection being adjusted according to the strength of the electric current, so that the speed of rotation is correspondingly altered, either directly through the 25 current to be measured by interposing a solenoid or indirectly through a branch current in which are interposed two electro-magnets acting in opposite directions.

The novel apparatus and several modified 30 constructions of the same are shown in the accompanying drawings.

Figure 1 shows a construction of the apparatus in which the intermediate connection is displaced directly by a solenoid. Fig. 2 is 35 an improved construction of the apparatus shown in Fig. 1, by which the revolving body can be simplified. Fig. 3 represents a construction similar to that of Fig. 2. Fig. 4 is a diagram of an apparatus in which the intermediate connection is displaced indirectly 40 through an electro-motor, (relay,) which is actuated when the strength of the electric current (tension and energy) is altered. Fig. 4^a shows a modification of the contrivance 45 effecting the actuation of the electro-motor, (relay.) Figs. 5 and 6 are modified constructions of the apparatus having the electro-motor, (relay.)

The apparatus consists of a revolving body 50 R, movable round a shaft A and put in uniform rotation by a mechanical or electric-

power motor, such as an electric pendulum. A shaft a is arranged parallel to one of the longitudinal sides s of the revolving body, the said shaft being adjustable in bearings 55 l l and carrying a frictional disk V. This disk V is rotated by frictional contact from the revolving body, and the rotation of the disk is more rapid the more the disk approaches the base B of the body R. The shaft 60 a carries a worm or toothed wheel g, by means of which the revolutions are registered by a counting device. When the shaft a is adjustable, it is connected by a feather connection to the worm g. It may be remarked 65 here that inversely the revolving body may be carried by the shaft a and the frictional disk by the shaft A, in which case the disk V is rotated by the mechanical or electric power motor, and communicates its rotary 70 motion to the body R. In other words, the body R and disk V are adjustable with relation to one another, and this adjustability can be secured by making either the rotary body or the disk adjustable, as desired. 75

For recording the current (tension or energy) used in a circuit during a certain space of time, it is only necessary to render the speed of rotation dependent upon the quantity, tension, and energy of the electric current at the 80 respective moment. This is done as follows: To the lower end of the shaft a an iron core k is secured, which is influenced by the electro-magnet or solenoid S, placed in the circuit.

The operation of the apparatus is as follows: As long as no current passes through the circuit, the core k penetrates up to a determined depth into the solenoid. The frictional disk V is in the height of the point t of the revolving body R, but it is not put in rotation. When, now, a current flows through the circuit, the core k is drawn deeper into the solenoid, the lower end of the core coming up from about the position marked by 1 to about the position marked 2, Fig. 1. By 85 this motion the shaft a and the frictional disk V are raised and the latter rotates at a speed corresponding to the circumferential speed of the diameter r². When the strength of current (tension and energy) increases in the circuit, the core is drawn deeper and deeper into the solenoid S, and in consequence the disk 90 100

V, owing to the continuously-increasing diameter of the revolving body, rotates more and more quickly. The revolution of the disk V depends, therefore, directly on the strength of current, (tension and energy,) so that the consumption of current can directly be determined by the recorded number of revolutions provided that the different radii $r' r^2 r^3$

B of the body R are proportional to the spaces 1 2 3 . . . . . b of the core K. To obtain this proportioning the revolving body cannot be a regular body, as the distances of movement of the core K, when the current is doubled or tripled in strength, are not of double or triple length; but the revolving body must be shaped, such as shown in dotted lines in Fig. 1. This shape, however, offers numerous difficulties.

To allow of the use of a regularly-shaped revolving body the generatrix of which is rectilinear, I attach to the core a suitably-shaped hollow or solid body s, (see Figs. 2 and 3,) immersed in a liquid contained in a vessel, so that either owing to the variable buoyancy (see Fig. 2) or owing to the variable loss of weight (see Fig. 3) the spaces traversed by the core K are proportional to the uniformly-increasing diameters of the body R.

As particularly in larger apparatus the force necessary for actuating the shaft a and the frictional disk V is a rather considerable one it is advisable to interpose an electromotor, (relay.) Fig. 4 is a diagram of such an arrangement.

From the main circuit H is led off a branch current flowing through two electro-magnets E' and E², the armatures a' and a² of the same, and the pins or contacts t' and t² to the contact-points c' and c², while the other pole is connected with the needle Z of a galvanometer, such as an ampère, volt, or watt meter.

Between the two electro-magnets is suspended a rack T, provided on opposite sides with teeth and moved upward by the extended armature a' and downward by the armature a². The upper end of the rack T carries two insulated contact-points c' and c², between which moves the galvanometer-needle Z. The rack T is connected by means of a cord with the shaft a, carrying the frictional disk V.

The operation is as follows: When no current passes through the circuit, the galvanometer-needle is at rest and the frictional disk is not rotated by the revolving body R. When a current passes through the circuit, however feeble the current may be, the galvanometer-needle will move and form contact with c'. The branch circuit is now closed, the electro-magnet E' attracts its armature a', and the rack T is moved one tooth upward. At the same moment the current is broken at t' the armature a' is drawn back again by its spring and the contact is by this re-established at t' and the rack moved again one tooth until the needle Z has arrived in a new rest position and the rack has been

raised to such an extent that the needle Z no longer touches the contact-point c'. In the same measure as Z is raised the rack T is also moved upward and the frictional disk V lowered, and the speed of rotation of the latter increases in the same proportion as the disk V approaches to the base B of the body R. The speed of rotation of disk V is therefore proportional to the stroke of the galvanometer-needle and in consequence to the quantity of the current passed through the apparatus, provided the graduation be correct. In lieu of fastening the contact-points c' and c² to the rack they may be connected also with the galvanometer-needle, as is illustrated in Fig. 4^a. There is in this case a simple contact-piece p applied to the rack.

Figs. 5 and 6 are modified constructions of the apparatus illustrated in Fig. 4.

The apparatus shown in Fig. 5 consists, as in the former case, of the revolving body R, the frictional disk V, movable with its shaft, the rack T, connected therewith, an electric pendulum P serving to actuate the revolving body by means of the pawl m and raising and lowering the frictional disk V, and the mechanism necessary for transmitting motion from the pendulum to the frictional mechanism with the relay actuating the latter.

The apparatus works in such a manner that the galvanometer-needle Z of the dial or meter A' moves between two contact-points c' and c², and according as it comes in contact with c' or c² the electro-magnet E' or E² is vitalized.

Between E' and E² moves the armature a³, carried by two spiral springs f' and f² and guiding the lever h, jointed to the pendulum P. When the armature a³ is attracted by the electro-magnet E' or E², the lever h is at the same time raised or lowered, and thus gears together with the toothed wheel Z' or Z². The corresponding toothed wheel is then turned one tooth at each stroke of the pendulum, and this motion is transmitted to the rack T, actuating the frictional disk V.

Fig. 6 shows an amperometer, consisting of a solenoid furnished with an iron core and effectuating the closure of the current.

The strength-tension or the energy of the current may be recorded as desired.

The advantages of this apparatus, compared with the hitherto-known contrivance, consists of the fact that even the smallest quantities of electricity are recorded and that the apparatus is independent of exterior influences. The apparatus may serve at the same time, also, for determining the current momentarily flowing through the circuit. For this purpose it is necessary only to apply to the rack T a needle moving over a scale. The apparatus is furthermore transportable without being exposed to be damaged by shocks, and the indications of the same are not exposed to the effects of varying temperatures. As the apparatus can be arranged for indicating the electricity passing at any moment through the

circuit, anybody is capable of controlling the exactness of the indications made.

Having now fully described the nature of our said invention and in what manner the same is to be performed, we declare that what we claim is—

In an electric measuring and registering apparatus, the combination, with a rotary body or surface, of a counting device, an intermediate connection between said rotary body and counting device, said connection and rotary body being adjustable with respect to one another, an adjusting mechanism, substantially as described, for regulating the ad-

justment of the rotary body and connection, 15 a motor or pendulum P, for actuating said rotary body and adjusting mechanism, and an electric motor or relay for bringing said motor P into connection with the adjusting mechanism, substantially as described. 20

In testimony whereof we have signed our names to this specification in the presence of two subscribing witnesses.

JACOB EINSTEIN.

SEBASTIAN KORNPROBST.
